(57) **CLAIM**

The ornamental design for a kettle, as shown and described.

DESCRIPTION

FIG. 1A is a front view of our kettle, comprising a flat bottom portion and a concave top portion shown in a closed position, the back view thereof being substantially identical; FIG. 1B is a left side view of our kettle, in the closed position, the right side view thereof being substantially identical;

FIG. 2A is a top view of the bottom portion of our kettle; FIG. 2B is a bottom view of the bottom portion of our kettle, being also the bottom view of the kettle in the closed position;

FIG. 3A is a top view of the top portion of our kettle, being also the top view of the kettle in the closed position;

FIG. 3B is a bottom view of the top portion of our kettle; FIG. 3C is a cross-sectional view of our kettle taken along the line A-A in FIGS. 3A and 3B, with the top portion separated slightly vertically above the bottom portion;

FIG. 3D is a partial, detailed view of the cross-sectional view of our kettle in FIG. 3C;

FIG. 4A is a partial, detailed top view of one of the side handles of our kettle, generally as shown in FIG. 3B;

FIG. 4B is a cross-sectional view of one of the side handles of our kettle taken along the line B-B in FIG. 4A;

FIG. 4C is a front view of one of the side handles of our kettle in the closed position; and,

FIG. 4D is a cross-sectional view of one of the side handles of our kettle taken generally along the line B-B in FIG. 3A, but in the closed position.

Our kettle comprises a flat bottom portion and a concave top portion adapted to nest inside the bottom portion in a closed configuration.
